United States Patent Office

Des. 184,923
Patented Apr. 21, 1959

184,923

BELT BUCKLE

Don V. Ellis, Seattle, Wash., assignor to Rodeo Cowboys' Association, Inc., Denver, Colo.

Application July 21, 1958, Serial No. 51,853

Term of patent 14 years

(Cl. D17—1)

Fig. 1 is a front elevational view of a belt buckle showing my new design;

Fig. 2 is an edge view thereof; and

Fig. 3 is a rear elevational view thereof.

I claim:

The ornamental design for a belt buckle, as shown.
